(57) **CLAIM**

The ornamental design for a passenger-accessible, flexible
portable motorcycle pouch, as shown and described.

DESCRIPTION

FIG. 1 is a perspective view of the passenger-accessible,
flexible portable motorcycle pouch, showing our new design;
FIG. 2 is a rear view of the design shown in FIG. 1.

FIG. 3 is a front view of the design shown in FIG. 1.

FIG. 4 is a left side view of the design shown in FIG. 1.

FIG. 5 is a right side view of the design shown in FIG. 1.

FIG. 6 is a top view of the design shown in FIG. 1; and,

FIG. 7 is a bottom view of the design shown in FIG. 1.

The broken lines represent stitching.
